[57] CLAIM

The ornamental design for a two spindle faceter, as shown and described.

DESCRIPTION

FIG. 1 is a front elevational view of a two spindle faceter showing my new design;

FIG. 2 is a top plan view of FIG. 1;

FIG. 3 is a side elevational view taken from the left of FIG. 1;

FIG. 4 is a side elevational view taken from the right of FIG. 1;

FIG. 5 is a rear elevational view of FIG. 1;

FIG. 6 is a bottom plan view of FIG. 1; and

FIG. 7 is a perspective view showing the faceting machine in an alternate position for use.

FIG. 1

FIG. 2

FIG. 3

FIG. 4

FIG. 5

FIG. 6

FIG. 7
